G. F. BAKER

SAFETY DANGER SIGNAL FOR RAILROAD TRACKS

Filed Aug. 19, 1927

Patented Sept. 18, 1928.

1,684,904

UNITED STATES PATENT OFFICE.

GEORGE FRANCIS BAKER, OF CINCINNATI, OHIO.

SAFETY DANGER SIGNAL FOR RAILROAD TRACKS.

Application filed August 19, 1927. Serial No. 214,168.

This invention relates to danger-signal devices for use in and along railroad-tracks and, more particularly, to the special purpose of warning those advancing on the track, where 5 workmen are at work ahead, so as to avoid damage or injury to either, and, initially, to the protection of said workmen.

The object of the specific improvement herein is to provide a convenient, light, strong 10 and economical means of supporting a signal device at any suitable point where danger threatens ahead, the use named above, in the railroad-track service, being well considered by me as one of the most fitting and desired, and intended to take the place of the make-shift and heavy means heretofore employed in such service that has always demanded extreme caution in passing along a track where men are at work in isolated 15 localities or where some other danger lurks or is present and ordinarily unknown to the trainmen and others employed in the running of trains.

The details of structure will be fully hereinafter described in connection with the accompanying sheet of drawings, in which—

Figure 1 is a transverse section of a railroad track showing attached to one of its rails the danger-signal device embodying my 30 invention herein in its preferred form; Fig. 2, a fragmentary transverse section of track, showing my device the same as in Fig. 1, but on a somewhat larger scale, and with the swinging jaw-member of the clamp in dotted lines and thrown open for the release of the clamp from the rail; Fig. 3, an outer-side elevation of the rail and clamp structure seen in Fig. 2; Fig. 4, a fragmentary elevation of the signal or target portion of the improvement 35 described herein and including an elevation of the grapple or tongs used in gripping the lantern when required; Fig. 5, a detached elevation of the said grapple or tongs, shown open ready for the insertion of the lantern-bail; Fig. 6, a vertical sectional elevation, 40 taken on line 6, 6, of Fig. 4, but showing the target in full diameter; and Fig. 7, a broken sectional plan, taken on the dotted-line x, x, through Figs. 2 and 3, flush with the tread 45 of the rail.

It will be noted, (to the left in Fig. 2), that I have shown the slideable lock-ring of the clamp-members in plan, side-elevation and end-elevation, to bring out more clearly the 50 detail structure of the said lock-ring.

A indicates the ordinary cross-tie; B, the

ground; and C, C, the ordinary pair of T-rails mounted on the said cross-tie in duly spaced relation to form a railroad-track, as customary.

The clamping device for supporting a lantern D and a target-signal E in said track, between the rails as is usually done, I will now proceed to describe.

A pair of vertical clamp-members is composed of two coinciding plates 7 and 8, pivotally connected together at F. The plate 7 has an upwardly-slanting arm 9 that extends (when in use) laterally half-way across the track for suspending the said lantern, topped by said target-signal E in due central relation with the track, between its rails C, C, all as best shown in Fig. 1, for ready and clear sight in every direction, but especially up and down the track, and indicating that the track is in the course of repairs or other construction work going on and men and material present several hundred feet, more or less ahead or back of the signal (in both directions up and down the track) to warn those approaching in either direction of the danger to them and to said workmen should they proceed further in the "block" (so to speak) until permission to pass through is first obtained, as is common in the use of what is called "blue-signals" for just such conditions when work is going on along a track or roadway.

The two plates 7 and 8 have coinciding rectangular jaw-formations or extensions 10 and 11, respectively, at their lower quarter-twisted ends 12 and 13, respectively, such jaw-formations being made to correspond in outline or contour with that of the head c of the rail and adapted to close upon said head c and encompass it in a firm manner when the signal device herein is in position for use. The outer jaw-formation 10 of the plate 7 is relatively longer than the inner jaw-formation 11 of the plate 8, as best seen in Fig. 3, 100 wherein the said shorter jaw-formation 11 is shown in vertical dotted lines, and, also, in Fig. 7, which is a sectional plan, taken on a line with the tread of the rail. The outer jaw-formation 10 is made the longer of the two so as to provide a better holding or gripping purchase on the side and under the head of the rail due to the additional weight or burden of the signals and their carrying arm that extend inwardly half-way across the track as above stated. Lower flanges 14 and 15, respectively, extend downwardly from the

jaw-formations 10 and 11 to embrace the upper part of the web *c'* of the rail in a firm and substantial manner, and thereby prevent the clamp from slipping laterally or cross-wise around the head of the rail, or elsewhere to suit the use of the portable signal device herein described.

An elongated lock-ring 16 is slid downwardly over the two plates 7 and 8 to hold them together when the jaws are in embracing or clamped position on the rail-head. The said two plates are tapered, with their coinciding broad lower ends terminating at the upper ends of the said quarter-twisted parts 12 and 13, the latter forming stops for the said lock-ring 16 to rest on when in seated place on the upwardly-extending clamp-plates 7 and 8.

A vertical series of horizontally-elongated holes or slots 17 is provided along one edge of the said assembled plates, to accommodate the loop 18 of a pad-lock 19 that is intended to prevent the said lock-ring being raised or moved from seated place on the closed clamp-plates and the device detached accidentally or surreptitiously otherwise from signaling position on the rail-head or wherever placed for danger-warning use. The elongated holes are provided to make due allowance for the clamping of the jaw-members on rail-heads or other supports of different dimensions or sizes and to make allowance for greater or lesser spread of jaw-members, the slot in the lock-ring and the taper of the plates 7 and 8 being made to meet the greatest spread of said jaw-members.

The target-signal E is mounted on the upturned outer end or terminal 20 of the target-arm 9 and, in order that the lantern D may be detachably secured at the said outer target-terminal of the arm 9, I provide a vertical bar or plate G that is attached at its upper end to the said upturned end 20 of the target-arm 9, with the lower part of the target intervening, all as best seen in Fig. 6. The lower end of said bar G extends centrally below said target E and has an upturned-hook formation H for the lantern-bail to rest in and to form a stop or housing to prevent the said lantern-bail becoming accidentally dislodged. A vertical latch-bar 21 is pivotally-mounted at 22 on the face of the lower extension of bar G and it has an L-shape jaw *g* at its lower end to register or partly coincide with the said hook H at the lower end of the stationary bar G. The upper end 23 of said latch-bar 21 is bowed or bent outwardly so as to pivotally accommodate one end of a stiff-wire pull-rod 24 that extends for pivotal-attachment at its opposite end to an elbowed or outwardly-bent arm 25 at the upper end of the vertical clamp-plate 8, as best seen in Figs. 3 and 6. When the latch-bar 21 is in closed position on the lantern-bail *g* that is seated or resting in the hook H of the

bar G it is securely maintained or kept so by means of the locked clamp-plates 7 and 8, and the lantern cannot be removed until the padlock 19 is released and the lock-ring slid upwardly along the said clamp-plates till it reaches the topmost point of its movement as shown in dotted lines in Fig. 2, at which time the jaw 11 and its pivotal carrying-plate 8 are shifted into the open position (also seen in dotted lines in Fig. 2,) whereby the said latch-bar is drawn into the open position seen in Fig. 5 and said lantern readily released.

When said padlock has been released and the lock-ring is in its topmost position (seen dotted in Fig. 2) the jaws 10 and 11 can be swung apart automatically by the weight of the target devices including that of the lantern, the entire device being held in one hand while the other hand is used in raising the said lock-ring to its said topmost position until the jaw-formations readily spread fully open so as to clear the head of the rail and then the device, being especially light and strong, can be handily moved elsewhere or shifted for further like service or stowed away in small compass when out of active use.

The device is readily adapted to other signal purposes than that of the track-work one mentioned and mostly desired, and it is always easily clamped into display position on either rail or on any convenient object that is chosen ahead of the danger point, and allows ample time for safety to all those approaching said danger point and within its zone.

The target can be varied at will to suit various signal purposes and the lantern can be dispensed with if desired. The target-arm 9 is preferably made of channelled metal for both lightness and strength.

I claim:—

1. In a device of the character described, the combination of a pair of tapered upright bars or plates having a series of aligning holes therein, clamping-jaw formations provided at the lower ends of said bars and adapted to be closed or spread apart by pivotal connecting-means at the upper ends of said bars, a slideable lock-ring encompassing the said pair of assembled tapered bars or plates and a suitable lock adapted to engage the said aligning holes in the assembled bars or plates for securing the latter in closed position together with the closed engagement of the said clamping-jaw formations on the head of a track-rail or other supporting object where warning of danger ahead is to be displayed, substantially as shown and described.

2. In a device of the character described, the combination of a pair of corresponding upright tapered bars or plates having a series of aligning holes therein and pivotally connected together at their upper ends,

clamping-jaw formations at the lower ends of said bars, a slidable encompassing locking ring on the said bars or plates when in assembled position, a removable lock adapted 5 to engage the said holes in the plates to suit the relative size of the object by which the device is to be supported or held in signalling position, a lateral arm extending from the upper end of one of said bars or plates, a target 10 mounted on said arm, a latch device pivotally mounted on said target-end of the arm and adapted to suspend a signal or warning lan-

tern and a pull-rod extending between the said latch device and an upright arm at the upper end of the companion bar or plate of 15 the clamping means and adapted to connect the jaw-members and the latch device so that they shall act in unison when the device is to be positioned for signal use or removed from using place, substantially as shown and described.

In testimony whereof I have hereunto affixed my signature.

GEORGE FRANCIS BAKER.
